UNITED STATES PATENT OFFICE.

CLIFTON L. BUNDY, OF PHILADELPHIA, PENNSYLVANIA, ASSIGNOR TO PHILADELPHIA ELECTRICAL & MANUFACTURING COMPANY, OF PHILADELPHIA, PENNSYLVANIA, A CORPORATION OF PENNSYLVANIA.

LAMP HANGER.

Application filed May 24, 1922. Serial No. 563,289.

One object of this invention is to provide a relatively simple, substantial, convenient device for removably supporting or suspending a street- or similar lamp in a raised or elevated position and more particularly to provide an automatically acting device for retaining or locking a member carrying said lamp in a holder when said member has been moved into or inserted within the same. 10 I also desire to provide a lamp hanger or holder with novel means whereby the lamp-carrying member supported therein may be quickly and conveniently disengaged and removed from said holder when desired. 15 Another object of my invention is to provide a novel form of supporting structure in combination with a member actuated by a rope or other flexible element passing through said structure, whereby said member 20 when drawn by the rope into the structure, is retained therein and supported thereby when the tension on said rope is released; the arrangement being such that suitable tension subsequently applied to and then removed from the rope will cause the member 25 to be automatically released and permit of its being lowered.

It is further desired to provide a compact, convenient and reliable device whereby successive manipulations of a supporting rope or cable will cause or permit the holding member first to be locked to and thereafter released from a supporting structure, the whole being so arranged as to be in no way interfered with by sleet, ice, or snow. 35

These objects and other advantageous ends I attain as hereinafter set forth, reference being had to the accompanying drawings, in which,

40 Fig. 1 is a side elevation showing my invention as used in connection with a lamp supporting pole and arm;

Fig. 2 is a front elevation of the device constituting my invention;

45 Fig. 3 is a side elevation partly in vertical section, further illustrating the device shown in Fig. 2;

Fig. 4 is a horizontal section on the line 4-4, Fig. 3;

50 Figs. 5 and 6 are respectively a front and a side elevation of the lamp carrying member;

Figs. 7 and 8 are respectively a side elevation and a plan of the retaining dog; and

Figs. 9 and 10 are fragmentary vertical sections taken at right angles to each other, illustrating modified forms of the upper end of the lamp carrying member shown in Figs. 5 and 6.

In the above drawings 1 represents a structure such as a mast arm, having a horizontally projecting arm 2 whose outer end is braced by inclined tie rods 3 and which at said end, carries a pulley 4 suitably journaled in a closed casing or fitting 5 communicating through said arm 2 with a second casing 6 whereby the inner end of the arm 2 (which is tubular) is connected to or mounted on the mast arm 1. This second casing likewise has mounted in it a pulley 7 which with the pulley 4, is so mounted that a rope or cable 8 passing upwardly around the pulley 7 may be carried through the tubular arm 2, around the pulley 4 and vertically downward therefrom through a vertically elongated casing 9.

A ball and socket joint is provided between the fitting 5 and the casing 9 so as to allow the latter to swing in all directions and always hang vertical, regardless of the position of the supporting arm. A bolt 10 permits the parts from becoming separated. The casing 9 is characterized by having adjacent its lower open end and at opposite sides thereof two inwardly projecting shoulders as shown at 11 in Fig. 3. Preferably these shoulders take the form of a complete annular ledge extending entirely around the casing. In addition, at a suitable point above these shoulders, the casing has an inwardly projecting rib or lug 12. When the shoulders 11 take the form of an annular ledge as described the lug 12 has somewhat less than 180° angular length and has its circularly curved edge 13 bevelled both upwardly and downwardly.

In accordance with my invention I mount a device such as an arc- or other lamp on a shackle 14 suspended centrally from a cross arm 15 by a pivot bolt 16. This cross arm is hung from a yoke 17 on the lower end of a carrying member 18 by a bolt 19 and said carrying member has the form of an elongated bar having a head 20 at its upper end perforated for the reception of the rope or cable 8, as shown in Figs. 5 and 6. Immediately below and to one side of said head the member 18 is laterally extended

and formed with a series of teeth 21 projecting from one face of said member in lines at right angles to the line of the opening 22 for the rope or cable.

- 5 This laterally extended upper part of the member 18 is provided with holes 23 for the reception of bolts 25 whereby a transversely toothed clamping plate 24 may be caused to grip the end of the rope 8 and so 10 attach it to the upper end of the member 18 as to effectually prevent its accidental withdrawal or loosening. Below this clamping portion the member 18 is formed with a slot or vertically elongated opening 26 in 15 which is horizontally pivoted a holding dog 27 carried on a pin or pivot 28 so as to be free to rotate into any position.

The dog 27 has two arms 30 and 31 projecting in opposite directions at right angles 20 to the pivotal axis and of a length greater than the distance between the shoulders 11. Thus the arms are adapted to support the lamp carrying member, and when there is an annular ledge as described the member 25 can assume any position of angular adjustment about a vertical axis. Provision is made for automatically moving the dog to bring the arms 30 and 31 into a vertical or approximately vertical position when the 30 carrying member is raised sufficiently to disengage the said dog from the shoulders. To this end the arm 30 is preferably made heavier than the arm 31 so that the dog tends to rotate into a position in which 35 the arm 30 is down. In this position the dog can pass freely between the shoulders 11.

In order that the arms 30 and 31 may be engaged with the shoulders 11, I provide 40 means dependent on the movement of the carrying member above a predetermined position for moving the said dog to bring the arms 30 and 31 into their horizontal shoulder engaging position. Preferably 45 this means comprised two arms 29, 29 on the dog 27, these arms being perpendicular to the arms 30 and 31 and being short enough to pass between the shoulders 11. These arms co-operate with the lug 12 in 50 a manner to be described.

With the above described arrangement of parts, after a lamp or other object has been attached to the shackle 14, it may be raised by tension exerted on the rope 8, and as 55 it nears the upper limit of its path of movement, the member 18 passes into the casing 9 with the dog 27 in such position that its arms 29 are horizontal. As the upward movement of the member 18 and its associated parts is continued, one of the arms 29 strikes and passes the rib or lug 12 and the whole structure is ultimately brought to rest by the head 20 striking on the inside 60 of the top of the casing 9.

65 If now the tension on the rope 8 be sud-

denly slackened off or reduced, the lamp attached to the shackle 14 and its associated parts causes the member 18 to move downwardly in the casing 9 so that an arm 29 of the dog strikes the upper beveled surface 70 18 of the rib 12, tilting said dog so that instead of passing through the open lower end of the casing, its arm 30 strikes the ledge 11 thereof, so that ultimately the two arms 30 and 31 both rest upon the same and assume a horizontal position across the opening, as shown in Fig. 3, supporting the weight of the member 18 and the lamp etc. 75 attached thereto.

Obviously no side swinging of the lamp 80 or any other ordinary forces to which it is exposed can dislodge the dog 27 from its given position, although when it is desired to lower the lamp for inspection or adjustment, this may be easily accomplished by 85 pulling on the rope 8 and raising the member 18 sufficiently to permit the long arm 30 of the dog to clear the ledge 11. Thereupon said long arm swings vertically downward and the short arms 29 assume horizontal 90 positions so that the dog is free to pass out of the open lower end of the casing 9.

From the above description it will be appreciated that my device, while being relatively simple and inexpensive to manufacture, is none the less durable, convenient and reliable under conditions of use. Moreover, owing to the fact that when the lamp-carrying member 18 is in its locked position its upper part, as well as the dog, lies within 95 and is protected by the casing 9, it is obvious that no accumulation of ice or sleet will interfere with its operativeness.

If it be desired that the casing 9 with its associated parts should be capable of swinging in but a single plane relatively to the fitting 5, its upper part may be made as shown in Figs. 9 and 10, with laterally projecting trunnions 33 designed to fit suitable bearings in the casing 5. 100

I claim:

1. The combination in a lamp hanger, of a supporting structure; a lamp carrying member; means for raising and lowering said member; a dog horizontally pivoted to the lamp carrying member and having two similar arms extending in opposite directions from the pivotal axis; and shoulders on said supporting structure for engaging the extremities of said arms when the latter are substantially horizontal, the said shoulders permitting the dog to pass between them when the arms are vertical or approximately so. 115

2. The combination in a lamp hanger, of a supporting structure; a lamp carrying member; means for raising and lowering said member; a dog horizontally pivoted to the lamp carrying member and having two similar arms extending in opposite direc- 120 125 130

- tions from the pivotal axis; shoulders on said supporting structure for engaging the extremities of said arms when the latter are substantially horizontal, the said shoulders 5 permitting the dog to pass between them when the arms are vertical or approximately so; and means for automatically moving the said dog to bring the arms into vertical position, when the carrying member is raised to 10 disengage the dog from the shoulders.
3. The combination in a lamp hanger, of a supporting structure; a lamp carrying member; means for raising and lowering said member; a dog horizontally pivoted to 15 the lamp carrying member and having two similar arms extending in opposite directions from the pivotal axis; shoulders on said supporting structure for engaging the extremities of said arms when the latter are substantially horizontal, the said shoulders 20 permitting the dog to pass between them when the arms are vertical or approximately so; and a counterweight on the dog for automatically moving it to bring the arms into 25 vertical position, when the carrying member is raised to disengage the dog from the shoulders.
4. The combination in a lamp hanger, of a supporting structure; a lamp carrying member; means for raising and lowering said member; a dog horizontally pivoted to 30 the lamp carrying member and having two similar arms extending in opposite directions from the pivotal axis; shoulders on said supporting structure for engaging the extremities of said arms when the latter are substantially horizontal, the said shoulders 35 permitting the dog to pass between them when the arms are vertical or approximately so; and means dependent on the movement of the carrying member above a predetermined position for moving the said dog to bring the arms into their horizontal shoulder engaging position.
- 40 5. The combination in a lamp hanger, of a supporting structure; a lamp carrying member; means for raising and lowering said member; a dog horizontally pivoted to the lamp carrying member and having two similar arms extending in opposite directions from the pivotal axis; shoulders on said supporting structure for engaging the extremities of said arms when the latter are substantially horizontal, the said shoulders 45 permitting the dog to pass between them when the arms are vertical or approximately so; and means for automatically moving the said dog to bring the first of said arms into their horizontal shoulder engaging position.
- 50 6. The combination in a lamp hanger, of a supporting structure; a lamp carrying member; means for raising and lowering said member; a dog horizontally pivoted to the lamp carrying member and having two similar arms extending in opposite directions from the pivotal axis; shoulders on said supporting structure for engaging the cross arm, when the carrying member is moved above a predetermined position, to move the said dog to bring the first of said arms into their horizontal shoulder engaging position. 55
- 55 60 65 70 75 80 85 90 95 100 105
7. The combination in a lamp hanger, of a supporting structure; a lamp carrying member; means for raising and lowering said member; a dog horizontally pivoted to the lamp carrying member and having two similar arms extending in opposite directions from the pivotal axis; shoulders on said supporting structure for engaging the extremities of said arms when the latter are substantially horizontal, the said shoulders permitting the dog to pass between them when the arms are vertical or approximately so; a cross arm on the dog shorter than the aforesaid arms; and a lug on the supporting structure for engaging the cross arm, when the carrying member is moved above a predetermined position, to move the said dog to bring the first of said arms into their horizontal shoulder engaging position.
